UNITED STATES PATENT OFFICE.

GEORGE F. GREEN, OF KALAMAZOO, MICHIGAN, ASSIGNOR TO HIMSELF,
OLIVER S. KELLY, AND SOL. J. HOUCK, OF SPRINGFIELD, OHIO.

ELECTRIC CASH AND PARCEL CAR.

SPECIFICATION forming part of Letters Patent No. 338,150, dated March 16, 1886.

Application filed September 14, 1883. Serial No. 106,401. (No model.)

To all whom it may concern:

Be it known that I, GEORGE F. GREEN, of Kalamazoo, county of Kalamazoo, State of Michigan, have invented a new and useful Improvement in Electric Cars for Cash and Parcels, of which the following is a specification.

In the accompanying drawings, Figure 1 is a plan view of a car embodying my invention. Fig. 2 is a bottom view thereof. Fig. 3 is a side elevation of the car with the holding-receptacle attached thereto. Fig. 4 is a plan view of the holding-receptacle. Fig. 5 is a plan view illustrating the manner of arranging the track in relation to the counters and cashier's desk. Fig. 6 is a side elevation illustrating the spring-board device for storing force to be employed in starting the car after it has been stopped at the cashier's desk. Fig. 7 is an end view of the same. Fig. 8 is an end view of a trip for stopping and reversing the car at a point between the ends of the track. Fig. 9 is a side elevation of the track showing the connection of the same with the circuit breaking and closing device under the counter. Fig. 10 is an end view of one of the rotating armatures, showing the relation of the brush-rollers thereto. Fig. 11 shows detail views of the brush-rollers and commutators. Fig. 12 is a perspective view of the adjustable brushes.

The invention has for its object the transfer of parcels or cash from one part of a store to another by means of a car propelled over a track by electrical force to any desired point, means being employed for arresting and reversing the line of travel of the car at the will of the person for the time desiring to use the same; and the invention consists in the means and the construction of the several parts thereof, of which an illustration and particular description will herein-after be given in connection with the accompanying drawings.

A track, $a a'$, of suitable conducting material, is supported by brace-rods b' , extending from shelving b , arranged in any suitable manner about the room in which the system is to be used and placed in any position to suit the location of the counters and the cashier's desk c , and to be within convenient reach of the person desiring to use the same.

The car is represented as applied to a spread track; but such is not absolutely necessary, as the two rails may be placed together and insulated from each other by any well-known method.

In the present instance I have illustrated the track as arranged to serve as the electrical circuit with the brace-supports b' and arch ties b'' , properly insulated by blocks b''' , of wood or other suitable material, where they join the tracks. I have also illustrated a car mounted upon driving-wheels ff , having non-conducting peripheries secured to their respective shafts $e e$, which are actuated by two rotating electric armatures, f'' , which receive their motion from electro-magnets g , that surround them. These magnets may be of any construction suitable for revolving the armatures. The batteries may be located at any convenient place in the room in which the transfer-system is operated, and may be of any well-known and approved form suitable for the purpose; or, when convenient, a dynamo may be used. The circuit from the batteries or dynamo connects with the track $a a'$, with the positive conducting-wire a'' , attached to the rail a , and the negative wire a''' to the rail a' , or vice versa, for the purpose of transmitting the current from the rail through suitable brushes and other intermediate means to the field-magnets, which will then cause the armatures and the wheels f connected therewith to revolve and propel the car in either of two directions, according as the direction of the current is changed. A switch suitable for the purpose is composed of the sliding bar i , attached by screws or other suitable means to the under side of the frame of the car, and having pivoted to one end the copper levers $v' v''$, which turn on pivots v''' , projecting from block v'''' , and are pressed by springs v^5 into contact with the points $w' w''$ of the circuit-wire f' as they are thrown from one of said points to the other by the movement of the sliding bar, so as to reverse the circuit. The brushes $d' d''$ have rods $d''' d''''$, which slide loosely through openings therefor made in the plates $d^5 d^6$, which are secured by screws or other suitable means to some part of the car, the said rods sliding vertically and being free to swing in said plates, so as to move or play

laterally, the longer rods in addition to passing through the said plate also passing through guide-arms d^7 d^8 . By allowing the brushes a vertical and a lateral play the car will run more smoothly than it would if the brushes were rigid and the ends of the bristles bore perpendicularly or vertically upon the rail in running the car. If desired, the shorter arms might be extended and passed through similar guide-arms; but this is not necessary. The current passes from the rail through brushes d^7 to plate d^5 , thence through arm d^9 to wire f' , thence to pivot v''' , thence through lever v'' to point w' , thence through wire f' , diagonally across to point w'' , thence through wire f' to field-magnet g , from thence through wire f' to plate d^{10} , through the same to wire f' , thence to magnet g , thence through wire f' to point w'' , thence through wire f' diagonally across to point w' , thence through lever v' and pivot v''' to wire f' , from thence through plate i' and rollers $l''l'$ to commutators g' , thence through both ends of the rotating armature to lower side of commutator, through brush-rollers $l'''l'''$ to plate i'' , thence across through plate b to plate i''' , thence through brush-rollers $m''n''$ to commutator g' , from thence through brush-rollers $m'''n'''$ and plate i'''' to plate d^{12} , to plate d^6 , thence to brush d'' and to track. The commutators $g'g'$ are formed with breaks or gaps $h'h''$, arranged at right angles to each other, as shown, so that the full force of the batteries may be applied to one armature at a time, while the gaps are passing the brush-rollers of the other. These rollers are located one in advance of the other, as shown, so that the circuit shall not take or burn metal from the commutator as the rollers pass from one side of the gap to the other in reversing the circuit from one side of the rotating armature-head to the other. The shafts e of the rotating armatures at their inner ends are angular and fit into a coupling, i^5 , so that the two will be connected together, in order that one engine will pull the other over dead-points to assist the car in starting, the inner ends of the shafts having their bearings in the journal-box i^6 , fastened by screws or other means to some part of the car-frame, and the said coupling i^5 fitting in the forked end of said journal-box. The plates $i''i'''$ of the brush-rollers are connected to the car-frame by screws, and a spring, i^7 , bears against the connecting plate b , so as to equalize the pressure of the said roller-brushes on the two commutators. When the current is reversed, to move the car in the opposite direction, the current passes through the field-magnet in the reverse direction to that already described, as will be apparent to the skilled in the art. The car moves in the direction that the switch-bar i is moved. The bar i is moved through a lever, n , which is connected at its lower end to the bar and at its upper end to the connecting-neck m^1 of the arms m^1m^2 , which are curved, as shown, and extend in opposite directions, and are supported from a bracket, o , by means of a bolt, m^5 , passed loosely through the neck

m^4 , so as to permit the said arms and lever to rock. The arms may be braced by rods m^7 , and they, together with the lever stand at $7c$ an inclination, as shown, so that one arm will always be higher than the other, in order that it may strike against a tripping device in whichever direction the car may be moving, so that when it strikes said tripping device 75 the arm coming in contact therewith will be depressed, and the lever moved so as to slide the bar i , and through it shift the levers $v'v''$, so as to change the direction of the current and reverse the movement of the car. The 80 tripping device may be a fixed block, n' , depending from one of the arch-ties at either end of the track, and arranged, as shown, one nearer one rail than the other, so that when the car moves in one direction the arm m' 85 will strike the tripper, and when in the opposite direction the arm m will strike the other tripper, and the switch-bar is moved so as to reverse the current and the direction of the movement of the car. $9c$

In order to enable a salesman to reverse the movement of the car, I place at as many points as found desirable a tripping-bar, n''' , pivoted, as shown in Fig. 8, to a bracket on one of the tie-braces, and operated by means of a cord, 95 n'''' , which will extend to within easy reaching distance of a salesman at a counter. By drawing on said rope the tripping-bar will be thrown out, so that one arm of the lever n will strike against it and be depressed, so as to slide the bar i to change the direction of the car. When the salesman releases the cord, a spring, n^5 , will restore the tripping bar or arm to its former position, and the car can move on in the opposite direction to that in which it 105 was moving.

In order to break the circuit and hold the car at rest at the cashier's desk, I pivot at $s's'$ to blocks b'' at one side of the track, an inclined frame or bar, q , so as to be disconnected from the circuit in such manner that it may be tilted or rocked, the said inclined bar normally being above the track, so that as the car runs upon the same by reason of its momentum, the brushes d' will be elevated above 115 the track and the circuit thus broken, when the car will remain at rest till the cashier tilts the bar, so as to lower it far enough to permit the brushes to again come in contact with the track, and thus close the circuit for the further 120 movement of the car. The tilting of the inclined bar is effected by the cashier pulling on the cord r , which is connected with the arm r^2 , attached to the tilting bar, as shown in Fig. 7. As soon as the cashier releases the 125 cord r , a spring, t , secured at one end to the block b'' , and bearing at its other end against the tilting bar q , restores the latter to its former position.

In order to store up power to be used in assisting to start the car after it is released by the cashier, I connect a spring-board, u , provided with a hook-catch, b^4 , at its lower end to an upright standard, x , attached in any

suitable manner to a post, x' , secured to the block b'' . To the spring-board I pivot at v one end of a ratchet-bar, w , which will pass through a slot, z , made in the standard x , the 5 teeth of the ratchet engaging with the standard at the lower edge of the slot, so that the standard acts as a pawl to hold the ratchet-bar. The ratchet-bar is preferably slotted longitudinally, as shown in Fig. 6, and into the slot 10 one end of a lever, y , pivoted to a bracket, y' , secured to the upright standard, enters, while the other end is connected by a cord, y'' , to the arm r^2 . Now, when the car strikes against the 15 spring-board u , it presses the latter backward, which carries with it the ratchet-bar w , the teeth of which catch with the standard, at the bottom of the slot z , and hold the spring-board back. At the time that the car strikes the 20 spring-board the hook b^4 enters the hole or perforation c' in the end of the car, and thus holds the car. When the car is to be returned to the track, the rope r is pulled, which lowers the bar q , and at the same time pulls on the lever y , so as to release the ratchet-bar from its 25 pawl, when the rebound of the board u will impel forward the car, the hook b^4 being thrown at such an angle by the forward movement of the board as to disengage from the car, so that the car will be started on its trip and the parts 30 be in position to act as at first.

The car, in addition to the wheels f , attached to the armatures, is provided with wheels p' p'' , having insulated peripheries, which are mounted upon a shaft, q' , journaled in slots r' 35 r'' , formed in the framing l of the car, so that the wheels may have a rising and falling motion to adjust themselves to any inequality in the track. An idler, t' , journaled in a bridge, t , secured to the car-frame, bears against the 40 axle q' , and holds the axle firmly in its bearings, while at the same time permitting it to adjust itself to the rising and falling of the wheels. The car is further provided with idlers u' , u'' , u''' , and u'''' , which rotate horizontally and 45 serve to keep the car upon the track. The car is also provided with a carrying-receptacle composed of a reticulated basket, d^4 , fitting within a frame, d^{13} , attached by thumb-screws d^{14} to brackets d^{15} , which are connected by any 50 suitable means to the frame of the car, so as to bring the basket beneath the car. This basket is suspended by means of cords e''' from a spring-roller, d^{16} , of any well-known construction, which is journaled in brackets d^{17} , 55 attached to the frame d^{13} . The basket is drawn down by a means of a cord, d^{18} , attached to the basket, and is restored to its position within the frame by the spring-roller. The opening in the frame d^{13} , above the basket-receptacle, is covered by a sheet of gauze or other 60 suitable reticulated material, d^{19} , so as to prevent the contents of the receptacle from being accidentally removed therefrom. The car having been returned to the track, as hereinbefore set forth, when a salesman wishes to 65 use the basket he establishes the circuit by any suitable means, and when the car reaches

him he breaks the circuit by the same means, and after the car has stopped pulls down the basket by means of cord d^{18} , places in the basket 70 what he desires, releases the cord, so that the spring-roller will carry the basket up to the car, and then re-establishes the circuit by the same means, and the car travels on to the cashier's desk, where it will be stopped by 75 means already described.

As means suitable for establishing and breaking the current, there may be employed a copper plate, y^5 , secured to the under side of the counter, and a copper wire, y^6 , suspended 80 by non-conducting loops y^7 from the counter beneath said copper plate y^5 , the said plate being connected by a wire with the track and the wire y^6 with the battery. By pressing the wire against the plate the circuit will be established, and by breaking the contact the circuit will be broken. There need be only one battery used, as the copper plate will extend along the under surface of the entire counter, and so will the wire which is suspended beneath the plate. Such being the case, the pressure of the wire into contact with the copper plate at any point throughout their length will cause the circuit to be closed at such point of contact and the current established between the rail and battery, as is obvious to the skilled in the art.

In addition to providing the car with the lever n and arms m m' , there may be provided cords r^3 , which will be connected to the sliding bar i at opposite ends, and will hang down from eyes at the ends of the car, so as to be within easy reach of the salesman. By pulling on this cord the sliding bar can be moved so as to shift the levers v' v'' and change the direction 100 of the current and the movement of the car as readily as by the rocking lever and tripping devices.

It is obvious that both or only one of the means may be used on the same car.

Having thus described my invention, what I claim is—

1. The combination of a track, a car to travel over the same, an electric motor connected with the car, means for charging said motor through the track to propel the car, means remote from the car for breaking or closing the circuit to start or stop the car at will, means for reversing the direction of travel of the car, and mechanism for automatically breaking the circuit between the car and track to bring the car to a rest, substantially as described.

2. The combination, with a track and car propelled over the same by electricity, of a switch for changing the direction of the current, a rocking lever connected with the car and said switch, and a tripping device for operating said lever, when the latter in the movement of the car comes in contact therewith to shift the switch, and thereby reverse the direction of travel of the car, substantially as described.

3. The combination, with a track, a car to

travel over the same, and an electric motor connected with said car, of the perforated plate and the rods having a vertical and lateral play in the perforations of the plate and 5 formed with brushes at their lower ends to come in contact with the rails, substantially as described.

4. The combination of the track, the car traveling over the same, the electric engine, 10 the commutators thereof, formed with gaps at right angles to each other, as set forth, the brush-rollers bearing on said commutators on opposite sides of the gaps, as described, means for transmitting the current through the brush 15 to the engine, and a switch to change the direction of the current to reverse the line of travel of the car, substantially as described.

5. The combination of the track, a recoil device adapted to be moved by a car striking it, 20 means for holding said device when so moved by the car, and means for releasing said device when the car is to be reversed in its movement, whereby the power stored by the car moving said device is utilized to impart momentum to 25 the car on the release of said device, substantially as described.

6. The combination, with a track and a car propelled over the same by electricity, of a device for breaking circuit between the car 30 and track, a recoil device for stopping the movement of the car, means for holding said recoil device to the position moved by the car, and means for closing circuit between the car and track and releasing the recoil device to 35 utilize the recoil of said device in propelling the car, substantially as described.

7. The combination, with the track and a car propelled over the same by electricity, of the tilting frame above the track to break the 40 circuit between the car and track, and means for lowering said frame to establish the circuit again, substantially as described.

8. The combination of the track, the spring-board, the slotted standard, the ratchet-bar pivoted to the spring-board and passed through 45 the slot of the standard, the lever engaging with the rack-bar, and means for operating said lever to release the ratchet-bar from the standard, substantially as described.

9. The combination of the track, the spring-board, the slotted standard, the ratchet-bar pivoted to the spring-board and passed through 50 the slot of the standard, the lever engaging with the rack-bar, the tilting frame, and the arm connected with said frame and the said 55 lever for lowering the frame and releasing the spring-board, substantially as described.

10. The combination of the track, the car, the car-axle adjustable to conform to irregularities in the track, and the idler holding said 60 axle in its bearings, substantially as described.

11. The combination of the track, the car to travel over the same, the electric motor connected to the car, the switch for changing the direction of the current through the motor, the swinging lever connected with the switch and having the curved arms in different vertical planes and extending in opposite directions, and the trips at or near each end of the track adapted to move said arms to reverse the line of travel of the car, substantially 70 as described.

12. The combination, with the car, of the frame supported beneath the car, the gauze within the frame, the spring-actuated roller, 75 and the basket suspended from the roller under the gauze in the frame, substantially as described.

In testimony whereof I have hereunto set my hand this 24th day of August, 1883.
